UNITED STATES PATENT OFFICE.

EDGAR ROUSE SUTCLIFFE, OF LEIGH, ENGLAND.

METHOD OF PRODUCING ACTIVATED CARBONACEOUS SUBSTANCES AND THE PRODUCT OF THE METHOD.

Application filed January 27, 1920, Serial No. 354,468, and in Great Britain February 1, 1919.

This invention relates to a method of producing so called "activated" carbonaceous substances, and to the product of the method.

It is known to subject charcoal to the action of steam whereby there is imparted to it the capacity of absorbing gases. The charcoal thus treated may be used as a gas filtering medium in gas masks intended for use in warfare or in mines. One of the objects of the invention is to produce similar carbonaceous material having a relatively great activity or capacity of absorption, by simple means involving economy in manufacture, and by the employment of coal or carbonaceous substances similar to coal.

Of the methods employed for activating charcoal that which it is preferred to use in carrying out the present invention is that which is well known involving the admission of steam to the charcoal heated to about 1000° C. that is to say under conditions in which the water gas reaction takes place and carbon mon-oxide and hydrogen are produced. It will thus be understood that by "activating" or "activated" is meant a known treatment applied to charcoal as described, separate and distinct from the process of distillation whereby the carbonaceous material as with charcoal has imparted to it a capacity for absorbing gases or similar properties not possessed by it before or without this treatment.

The invention is in part based upon the methods of producing fuel according to prior and existing patents, in which carbonaceous substances of the character of coal are reduced to a finely divided condition, and in that condition compressed without a binder to produce blocks which are coked, whereby a coked fuel is produced having characteristics distinct and different from ordinary coke. One of the objects of the present invention it will be understood is to utilize coal in a finely divided condition as the starting raw material, the coal being compressed into blocks which are then coked, and activated, to impart to the material the capacity of absorbing gases. The invention broadly comprises such a method of producing carbonaceous substances having gas absorbing properties.

According to the invention I reduce coal, such as bituminous or semi-bituminous coal to a substantially uniform condition of extreme fineness, such as represented by the

passage of the whole or a considerable part of the material through a very fine screen, for example a screen having 200 meshes to the linear inch, and I mix with the coal in this very finely divided condition, a proportion of previously activated carbonaceous material, that is, material that has already been treated, according to the present invention for imparting to it gas absorbing properties; a proportion found effective is 3 parts by weight of coal to 1 part by weight of the activated material. It will be understood that the activated material is preferably the activated coke previously produced according to the invention. The mixture which is uniformly and intimately effected is then compressed into blocks for example according to the method described in the specification of the prior Patent No. 1,267,711 of 1918, and the blocks produced are coked. As described in the specification of the said prior patent, blocks may be produced from the finely divided material by compression within a tapered mould in which the block or briquet on production is moved during the compression to permit of its laterally expanding in a larger part of the mould or in the interval between successive compressions. The coked material may advantageously then be crushed or broken down to 1 inch mesh, and fines may be eliminated. The material whether crushed or broken down or not is then activated.

It will be understood that the mixture and proportions are indicated by way of example and no limitation is made thereto.

According to the invention the coked material produced is activated within a retort which is internally heated, air or steam, or both air and steam being admitted into the retort with the heating gas for example 1000° C., so as to effect partial combustion, or the partial utilization of the carbon in the material treated, so as to produce water gas. The treatment may be continued according to the capacity of absorption desired. By such means the material has imparted to it the capacity of absorbing gases.

According to the invention vertical retorts are advantageously employed for this treatment, in and through which the coked material is continuously fed, and from which it is continuously discharged, activated. The rate of feed may for example, in the use of a small retort be about 8 lbs. per hour, while

the rate of discharge, taking account of the proportion of carbon lost in the treatment or utilized in partial combustion or in the manufacture of water gas, may for example 5 be about 6 lb. per hour.

Apparatus for effecting the activation may be of the type described in the specification of the prior application Serial No. 234,277 dated the 13th May, 1918, and as illustrated 10 in the accompanying drawing which represents a diagrammatic section of a vertical retort in which the treatment may be effected by internal heating.

A series of such vertical retorts *a* may be 15 provided with alternate regenerators *c*, *c*¹, which latter may be alternately heated by the combustion of gas and air (part of the make of gas in the coking plant or retorts for this purpose being advantageously 20 used), and have gas (which may also be part of the make of gas from the coking plant or retorts) passed through the regenerators for being heated before circulation as the heating medium through the retorts 25 for activating the charge therein, the gas being passed into the regenerators through a nozzle *g*. The regenerators *c*, *c*¹ are heated to a temperature for example of 1200° C. and the heating gas is maintained for example 30 at a temperature of 1000° C.

By providing a number of regenerators alternately with a number of retorts, hot gas may be continuously passed through the respective retorts.

35 The regenerators *c*, *c*¹ employed may be of any suitable construction. They may be vertically disposed in positions intermediate of the retorts *a*, and they are provided of such capacity as to ensure that all the retorts 40 of the battery or series may be kept supplied with heated gas for continuously heating the charge therein, adjacent regenerators being advantageously alternately heated, while the gas used as the heating medium for circulating through the retorts, 45 is being heated in others previously heated.

When heating the regenerator or blast stove *c* or *c*¹ the valve or damper closing communication with the lower end of the middle or main part of the retort *a* is closed and gas and air admitted to the lower part of the blast stove through the flue *i*. The flue *f* at the upper end of the blast stove has its outlet valve *j* open and the valve *h* between the upper part of the blast stove and the retort is closed, so that thus the combustion gases pass upwardly and through the outlet flue. After one blast stove has been heated the valves of the respective blast stove are reversed and cold gas is then injected into the upper part of the heated blast stove, while the cooled blast stove is then heated, the alternate heating of the respective blast stoves taking place at suitable periods.

The upper part of the retort *a* is advantageously diverted to one side as at *k*, and at that side the carbonaceous material is delivered whereby its slides or falls down into the upper part of the retort. An outlet 70 *l* is provided in the upper part of the retort as hereinbefore described through which gas and vapours may pass for condensation and purification, part of the gas produced being then utilized for heating the blast stoves and for heating the charge in the retorts in the manner described. 75

At the bottom of the lower part of the retort *a* an inclined surface *m* is provided beneath the retort by means of which part 80 of the weight of the charge may be supported, and this inclined surface may form part of a shoot by which the charge may be directed into a movable receptacle into which the residue may periodically be discharged. 85 At the end of this inclined surface a hinged plate *n* may be provided adapted to be operated from the outside of the shoot, so that it may be brought from a position in which it lies at right angles with the inclined surface and forms a stop to hold the charge, to a position in which it depends vertically from the lower edge of the inclined surface, so that the charge that lies upon the inclined surface may thus, being unsupported, fall 90 into the receptacle.

It will thus be understood that the regenerators or blast stoves *c*, *c*¹ are used in alternate periods, one of them being used for the combustion of gas and air for heating the regenerator or blast stove while in the other gas from the retort *a* is circulated. Thus when the blast stove *c* is being heated a damper or valve closes the port communicating with the lower part of the retort *a*, the 100 corresponding valve *j* is open and the corresponding valve *h* is closed, and a supply of gas and air is admitted through the corresponding flue *i* and is ignited for heating the brickwork, while in the regenerator or blast stove *c*¹ the corresponding valve *j* is closed and the corresponding valve *h* is open, and the damper is withdrawn to open communication in the lower part of the retort *a* 105 with the lower part of the regenerator or blast stove *c*¹ and gas is admitted through the nozzle *g* for causing a circulation of gas from the upper part of the retort *a* downwardly through the regenerator or blast stove *c*¹, then upwardly through the retort *a* 110 continually. On the regenerator or blast stove *c*¹ cooling down and the regenerator or blast stove *c* being heated, the valves are reversed to permit of the regenerator or blast stove *c*¹ being heated and the regenerator or blast stove *c* being used for the circulation through it of the gas from the retort in the manner described for imparting heat to the gas so that thus heated gas either from the 115 regenerator or blast stove *c* or *c*¹ passes with- 120 125 130

out substantial interruption through the charge in the retort *a* and thus the carbonization of the charge is continuously effected as the charge is withdrawn through the shoot *m* and is charged at the inlet *k*. Vertical regenerators having the usual regenerator brickwork may be employed, but any suitable means of producing heated gas for circulation through the charge in the retorts may be employed.

The retorts may in part be heated externally in known manner.

The product of the invention may be used for various purposes, that is to say it may be used for the filtration of fluids and to act by absorption or catalysis. Furthermore the product may be used for the purposes for which treated charcoal has been employed. The product may for example be used for the absorption of methane and hydrocarbons from coal gas with a view to produce a gas rich in hydrogen or it may be used for the absorption of benzol and other hydrocarbons and of ammonia. The product may furthermore be used for the purpose of absorbing moisture from air and after being reduced to a finely divided condition it may be used for manure and for the improvement of the soil.

I claim:

1. A method of producing an activated coke consisting in reducing coal to a substantially uniform condition of fineness, then compressing the coal into blocks without the

addition of any binder and without the addition of any non-carbonaceous substance, to produce a stone-like block, then coking the block and then activating it, substantially as described.

2. A method of producing an activated coke consisting in reducing coal to a substantially uniform condition of extreme fineness, admixing therewith a proportion of already activated coke in a finely divided condition, compressing the mixture to produce blocks, coking the blocks for the production of a residue, and then activating this residue.

3. A new article of manufacture being an activated coke that is solid, coherent, homogeneous and dense, and which coke has a re-constituted cellular structure distinct from the raw coal from which it was produced and contains a very large number of cells per unit of mass, and thus has a high gas absorbent capacity, substantially as described.

4. In a method of producing an activated coke as specified in claim 1 the step of adding to the coal in a substantially uniform condition of extreme fineness before compression to produce the block, a proportion of another carbonaceous substance also in finely divided condition, which substance is adapted to develop the porosity of the block on coking it, substantially as described.

EDGAR ROUSE SUTCLIFFE.
